UNITED STATES PATENT OFFICE.

WILLIAM F. BOUCHÉ, OF BUFFALO, AND CARL HARTMANN, OF LANCASTER, NEW YORK,
ASSIGNORS TO GOULD COUPLER COMPANY, A CORPORATION OF NEW YORK.

ELECTRIC REGULATOR.

1,307,845.

Specification of Letters Patent. Patented June 24, 1919.

Application filed March 15, 1916. Serial No. 84,317.

To all whom it may concern:

Be it known that we, WILLIAM F. BOUCHÉ, a citizen of the United States, resident of Buffalo, county of Erie, State of New York, 5 and CARL HARTMANN, a subject of the Emperor of Germany, and resident of Lancaster, county of Erie, State of New York, have invented certain new and useful Improvements in Electric Regulators, of which 10 the following is a specification.

The invention relates to improvements in electric regulators and more particularly to regulators in which a pile of resistance members, such as carbon blocks, are employed to 15 vary the electrical resistance of a circuit. The invention is particularly adapted to automatic regulators of this class and the invention may be applied to the regulation of any circuit. While it is particularly useful 20 in the regulation of the voltage applied to a lamp circuit in car lighting systems, it may also be used to regulate the generator field current and in other situations. The various 25 novel features and combinations will more clearly appear from the detailed description given below, taken in connection with the accompanying drawings, which form a part of this specification.

In the drawings Figure 1 is a front elevation of a regulator embodying the improvements in one form, the right half of the figure being largely in section; Fig. 2 is an end elevation of the regulator of Fig. 1, and Fig. 3 is a diagram illustrating the regulator in series with the lamp circuit of an electrical system of distribution, such as an axle driven car lighting system.

Referring to Figs. 1 and 2, 1 represents a suitable panel or base plate to which is attached two supporting frames 2, by means of bolts 3. Carried by and extending between the frames 2 are four rods 4, extending through and supporting tubular glass rods 5, which support and guide the carbon pile 6 composed of a series of carbon resistance disks or members.

A supporting rod or frame 7 is situated above the pile 6 and in proximity thereto, so that it will be affected by the heat of the pile 6. The rod 7 is provided with slots 8 through which loosely pass screws 9 into extensions of the frame 2 so that the rod 7 is free to slide longitudinally of the pile 6 on said extensions, being guided in such movement by the screws 9 in the slots 8. Each

end of the rod 7 is forked at 10 and in each forked end is pivoted a lever 11. Each lever 11 is connected respectively to an operating member or head 12 at each end of the pile 6 by means of two links 13 and suitable pivot pins, the links being held in place by means of double U-shaped straps 14, secured together in the center between the two links by means of a bolt 15.

The lower end of each lever 11 carries an antifriction roller 16, adapted to be engaged by the head 17 of a screw adjustably secured in the upper end of a lever 18. The levers 18 are respectively pivoted in the opposite forked ends of a supporting rod or frame 19, 65 slidably mounted longitudinally of the pile 6 in brackets on the frames 2 and guided in such movement by screws 20 passing through suitable slots in the rod 19 and into the frames 2. The rod 19 is sufficiently close to 70 the pile 6, so that it expands, due to the heat therefrom. Flat springs 21, secured respectively to the levers 11 by screws 22, have their ends bear against the frames 2 and tend to keep the rollers 16 in engagement 75 with the heads 17 and take up backlash.

Pivotedly connected respectively to the lower ends of the levers 18 are links 23, the downward motion of said links 23 being limited by arms 23', the other ends of 80 the links 23 being both pivotally connected to the stem 24 of a core or plunger 25, operated by an electromagnetic solenoid 26. The solenoid is provided with a surrounding magnetic structure 27 and graphite 85 rings 28, which serve as anti-friction guiding means for the stem 24 and core 25, the magnetic structure 27 being secured to the base plate 1 by screws 29. The solenoid structure also includes a dashpot 29' having 90 a dashpot mechanism consisting of a piston 30, having an internal cylinder 31 rigid therewith and through the upper end of which extends a stem 32, rigid with the core 25. The stem 32 has a head at its lower 100 end which is normally pressed against a seat in the lower end of the cylinder member 31 by means of a spring 33. The lower end of the dashpot is provided with an outlet closed by a set screw 34. Two adjustable 105 springs 35 act respectively on the links 23 tending to pull them downwardly and cause them by a toggle action to operate the levers 18, which in turn actuate the levers 11 and through links 13 connected to the head 110.

plates 12, compress the pile 6 or decrease its resistance.

In operation, when the strength of the solenoid 26 increases, the core 25 is raised. 5 This causes the links 23 to simultaneously operate both levers 18, by reason of the toggle arrangement so that levers 11 are permitted to move outwardly or separate and thus decrease the pressure on the pile 10 6 and increase its resistance. The solenoid 26 is relatively short and the core and magnetic circuit thereof are so constructed that 15 relative movement of the core 25 to operate the operating members at each end of the pile 6 materially alters the magnetic pull on the core or armature 25, whereby, as the core is attracted the magnetic pull is materially increased with material increase in the magnetic turns of the solenoid. Thus 20 as the opposing action of the springs increase due to their becoming stretched, the magnetic pull correspondingly increases, so that with a given voltage applied the apparatus will be maintained in equilibrium with 25 the core in various positions. This makes the apparatus extremely sensitive. By the inter-connecting of the operating parts at each end of the pile, through the rods 7 and 19, all of the working strains are taken 30 by the active parts of the regulator instead of through the base 1. By placing the rods 7 and 19 so that they are affected by the heat of the pile 6 they have a tendency to expand and contract with the pile 6 and 35 thus compensate for the effect of temperature on the regulator which would cause a greater displacement of the core 25 in the solenoid as the pile expanded if at the same time the rods 7 and 19 did not expand so 40 as to more or less correspondingly separate the pivot points of the levers 11 and 18. This compensation is permitted by the slotted and sliding arrangement of the rods 7 and 19, which permits them to move freely 45 longitudinally of the pile 6. This arrangement also permits the pile 6 and operating mechanism to adjust themselves laterally, so that there will be no binding between the plunger 25 and stem 24 and their bearings. 50 Thus either one or both of the screws having their heads 17 may be adjusted without throwing the core 25 out of alinement, as the pile 6 and operating mechanism at each 55 end will shift to maintain the core in proper alinement.

Referring to Fig. 3, 40 represents a generator adapted to charge a battery 41 and supply lamps or other translating devices 42. The regulator is shown with the carbon 60 pile 6 connected in series between the battery and lamps and the solenoid coil 26 connected across the lamp circuit, so that any tendency for the voltage across the lamp circuit to vary, due to variations in voltage 65 across the battery, is corrected by the regu-

lator, which acts to vary the resistance in circuit with the lamps, so as to maintain the voltage across the lamps substantially constant, as will be clear to those skilled in the art.

It will be obvious that many changes and modifications may be made and the invention embodied in radically different forms. Hence it is desired to cover all embodiments and structures which come within the language of the appended claims, and the equivalents thereof.

What is claimed is:

1. A regulator comprising a pile of resistance members, lever mechanism acting on one end of said pile to vary the resistance thereof, lever mechanism acting on the other end of said pile to vary the resistance thereof, a relatively fixed support for the pile, electromagnetic means for operating both 35 of said lever mechanisms simultaneously and means supporting said lever mechanisms relatively movable with respect to said relatively fixed support for the pile.

2. A regulator comprising a pile of resistance members, mechanism acting on one end of said pile to vary the resistance thereof, mechanism acting on the other end of said pile to vary the resistance thereof, a relatively fixed support for the pile, electromagnetic means for operating said mechanisms, and means supporting said mechanisms relatively movable with respect to said relatively fixed support for the pile.

3. A regulator comprising a pile of resistance members, relatively fixed supporting means for said pile, a means for varying the resistance of said pile, comprising a member operating on each end of the pile and relatively movable with respect to said supporting means, electromagnetic means for operating said resistance varying means, and supporting means for said resistance varying means, relatively movable with respect to said first mentioned supporting means.

4. A regulator comprising a pile of resistance electrodes, a relatively fixed support therefor, members adapted to operate on each end of said pile to vary the resistance thereof, and a support for said members relatively movable with respect to said pile and fixed support.

5. A regulator comprising a pile of resistance electrodes, members adapted to operate on each end of said pile to vary the resistance thereof, and relatively movable supporting means for said members, permitting their movement with respect to the pile without varying its resistance.

6. A regulator comprising a pile of resistance electrodes, members adapted to operate on each end of said pile to vary the resistance thereof, and relatively movable supporting means for said members, permitting their movement with respect to the pile.

without varying its resistance, a toggle arrangement for operating said members to vary the resistance of said pile and electromagnetic means for operating said toggle arrangement.

5 7. A regulator comprising a pile of resistance electrodes, a relatively fixed support therefor, lever members adapted to operate on each end of the pile to vary the resistance thereof, and relatively movable supporting means for said lever members, permitting their movement with respect to the pile without varying its resistance.

10 8. A regulator comprising a pile of resistance electrodes, a relatively fixed support therefor, lever members adapted to operate on each end of the pile to vary the resistance thereof, and relatively movable supporting means for said lever members, permitting their movement with respect to the pile without varying its resistance, second levers, one for operating each of the first two mentioned lever members and electromagnetic means for simultaneously operating said second levers.

15 9. A regulator comprising a pile of resistance electrodes, a relatively fixed support therefor, lever members adapted to operate on each end of the pile to vary the resistance thereof, and relatively movable supporting means for said lever members, permitting their movement with respect to the pile without varying its resistance; second levers, one for operating each of the first two mentioned lever members and electromagnetic means for simultaneously operating said second levers, and relatively movable supporting means for said second levers, permitting of their movement with respect to the pile without varying its resistance.

20 10. A regulator comprising a pile of resistance electrodes, a relatively fixed support therefor, lever members adapted to operate on each end of the pile to vary the resistance thereof, and relatively movable supporting means for said lever members, permitting their movement with respect to the pile without varying its resistance, second levers, one for operating each of the first two mentioned lever members, a toggle arrangement operating said second levers simultaneously, and an electromagnet operating said toggle arrangement.

25 11. A regulator comprising a pile of resistance electrodes, a relatively fixed support therefor, lever members adapted to operate on each end of the pile to vary the resistance thereof, and relatively movable supporting means for said lever members, permitting their movement with respect to the pile without varying its resistance, second levers, one for operating each of the first two mentioned lever members, a toggle arrangement operating said second levers simultaneously, and an electromagnet operating said toggle

arrangement, and relatively movable supporting means for said second levers, permitting of their movement with respect to the pile without varying its resistance.

12. A regulator comprising a carbon pile, 70 fixed supporting means therefor, a relatively movable frame member, and means operating on both ends of said pile connected to said frame member and relatively movable with respect to said supporting means. 75

13. A regulator comprising a carbon pile, fixed supporting means therefor, a relatively movable frame member, slidably mounted longitudinally of the pile, and means operating on both ends of said pile connected to 80 said frame member and relatively movable with respect to said supporting means.

14. A regulator comprising a pile of resistance members, a relatively fixed supporting means therefor, members relatively movable with respect to said fixed supporting means and operating on each end of said pile to vary its resistance, and a toggle arrangement for operating said members to vary the resistance of both ends of the pile simultaneously. 85

15. A regulator comprising a carbon pile, fixed supporting means therefor, a relatively movable frame member, situated in proximity to the pile where it will be affected by heat from the pile so that it will expand therewith, and means operating on both ends of said pile, connected to said frame member and relatively movable with respect to said supporting means. 95

16. A regulator comprising a pile of resistance electrodes, supporting means therefor, a frame member, situated in proximity to the pile where it will be affected by heat from the pile so that it will expand 105 therewith, and means operating upon the end of the pile to vary its resistance, said means being connected to said frame member whereby the operating position of said means is varied by expansion of the said 110 frame member.

17. The combination with a regulating element the effect of which is altered by variations in pressure thereupon, of pressure controlling means operating upon each 115 end of said element, a toggle joint uniting and coöperating with said means, and electromagnetic means for moving the knuckle of said joint.

18. The combination with a regulating 120 element the operation of which may be altered by variations in pressure thereupon, of levers for exerting pressure upon both ends of said element, and a toggle joint uniting said levers whereby movement of the 125 knuckle of said joint affects said element, electromagnetic means for moving said knuckle in one direction, and means tending to move the knuckle in a different direction. 130

19. The combination with a regulating element the effect of which is varied by variations in pressure, means for controlling the pressure upon said element comprising a plurality of levers operating thereupon, a toggle joint coöperating with said levers, and electromagnetic means for moving the knuckle of said joint.
20. The combination with a regulating element the operation of which may be altered by variations in pressure thereupon, of levers for exerting pressure upon both ends of said element, and a toggle joint uniting said levers whereby movement of the knuckle of said joint affects said element, and electromagnetic means for moving said knuckle.
- In testimony whereof we have signed our names to this specification.

WILLIAM F. BOUCHÉ.
CARL HARTMANN.
